Electric Wine Bottle Opener, posted Aug. 28, 2021 [online], [retrieved Mar. 9, 2023]. Retrieved from internet, <https://www.amazon.com/Electric-Operated-Corkscrew-Automatic-Reusable/dp/B09DVDB2ZH/> (Year: 2021).*

Primary Examiner — Calvin E Vansant
Assistant Examiner — Benjamin L. Gray

(57) **CLAIM**

The ornamental design for an electric wine opener, as shown and described.

DESCRIPTION

FIG. 1 is a perspective view of an electric wine opener showing the new design.

FIG. 2 is an enlarged view of a portion labeled "FIG. 2" in FIG. 1.

FIG. 3 is an enlarged view of a portion labeled "FIG. 3" in FIG. 1.

FIG. 4 is a front view of the electric wine opener of FIG. 1.

FIG. 5 is a rear view of the electric wine opener of FIG. 1.

FIG. 6 is a side view of the electric wine opener of FIG. 1.

FIG. 7 is an opposite side view the electric wine opener of FIG. 1.

FIG. 8 is an enlarged top view the electric wine opener of FIG. 1; and,

FIG. 9 is an enlarged bottom view the electric wine opener of FIG. 1.

The dashed lines in the figures illustrate portions of the electric wine opener that form no part of the claimed design. The dash dot dash lines in FIGS. 1, 2 and 3 are for the purpose of illustrating the enlarged view indicators and form no part of the claimed design.

1 Claim, 9 Drawing Sheets
